PHONOGRAPH

Lester L. Jones, Oradell, N. J., and Thomas E. Piazzese, Brooklyn, N. Y., assignors to Technidyne Corporation, New York, N. Y., a corporation of New York

Application January 8, 1930, Serial No. 419,265

12 Claims. (Cl. 274—10)

This invention relates to phonographs and more particularly to control means for automatic phonographs.

In automatic phonographs it is customary to supply records in succession from a record supply magazine to the phonograph turntable. As each record is played it is discharged from the record turntable and replaced by a new record to be played, but when the last record in the magazine has been played it is desirable to automatically stop the phonograph. One primary object of our invention resides in the provision of means for discriminating between the presence and the absence of a record on the turntable in order to control the operation of the phonograph. More specifically, we are concerned with electrically operated phonographs, and this object of our invention is to provide a no-record switch for opening a phonograph circuit when there is no record on the phonograph turntable. This we accomplish by utilizing a reproducer which is both horizontally and vertically reciprocable in the usual manner, and providing a no-record switch which is operated in response to the vertical reciprocation of the reproducer, that is, its movement toward and from the record.

A further object of our invention is to apply the no-record switch so far described to an automatic phonograph of the type disclosed in copending applications of Lester L. Jones, Ser. Nos. 341,076, 341,077, and 341,078, now Patent No. 1,954,246, granted April 10, 1934, filed February 19, 1929, and to embody said switch in the control circuits for such a phonograph, disclosed in our copending application Ser. No. 403,252, filed October 29, 1929, now Patent No. 1,954,247, granted April 10, 1934. In this automatic phonograph the record changing operation is performed by oscillating the record turntable about a horizontal axis. The used record is discharged from the record turntable during the downward oscillation thereof, and the record to be played is picked up by the centering pin of the turntable during the upward oscillation thereof. The record and the reproducer are brought into contact by positioning the reproducer near the peripheral edge of the record, and preferably over the blank peripheral margin thereof, and raising the record directly into contact with the reproducer during the upward oscillation of the turntable. Obviously, during the record change operation the reproducer drops to a level lower than when resting on the record, and it is raised by the record to be played. This movement may be used to discriminate between presence and absence of a

record on the turntable, and may be made very certain in operation by making the turntable substantially smaller than the records to be played so that in the absence of a record the reproducer is not at all elevated when the turntable is raised. 5

From the foregoing brief description it will be understood that the automatic phonograph is provided with stop means for locating the reproducer near the periphery of the record during the upward oscillation of the turntable. In order to insure that the reproducer stylus will be started in the first sound grooves of the record the stylus is preferably positioned over the blank peripheral margin of the record, and is moved 15 gently inward toward the sound grooves of the record after the record and stylus have been brought into engagement. This movement may, if desired, be aided by a light spring, but preferably is obtained by making the oscillatable reproducer arm substantially longer than the distance between its center of oscillation and the conventional approximately radial (relative to the record) arc of reproducer travel over the record or, more broadly, by bringing the record and 20 reproducer into contact at a point the motion of which or the tangent to which is at a substantial angle inward of the record relative to a line passing through the reproducer stylus and the center of oscillation of the reproducer arm, that 25 is, a line perpendicular to the direction of movement of the reproducer. With this construction the drag of the rotating record on the stylus draws the stylus toward the first sound groove 30 of the record. 35

It will be clear that a stop is needed which will position the reproducer at a point adjacent the periphery of the record, but which will free the reproducer for inward movement when the record comes into playing position. If only one size 40 of record is to be played, say ten inch records, this stop may be fixed in position inasmuch as the stylus is first deposited on the blank margin of the record. Another object of the present invention is to provide stop means for the reproducer which will take advantage of the foregoing facts and fulfill the foregoing requirements. With this in view we provide the phonograph chassis with a fixed stop, and provide the reproducer arm with means movable upon vertical 45 reciprocation of the reproducer for engaging the fixed stop. The fixed and movable stop means are so relatively located that when the reproducer rests upon a record the means carried thereby is moved out of engagement with the 50 55

stop means, thereby freeing the reproducer for inward movement over the surface of the record. When the operation of the phonograph so far described is carefully analyzed we have found that it is desirable that the reproducer be permitted to move inwardly of the record as the reproducer is raised by the record in addition to completely freeing the reproducer for inward movement when the record finally reaches its normal playing position. This movement is necessitated by the lengthening of the reproducer arm when the arm is elevated to a more nearly horizontal position, and by the movement of the record toward the center of oscillation of the reproducer arm when the record is moved into playing position, these factors being taken in combination with the inwardly directed movement of or tangent to the record at the point of contact thereof with the reproducer as was previously described. Accordingly, a further object of our invention is to devise stop means which may be of simple and fixed form, and yet which will permit the reproducer to move inwardly of the record during the raising of the reproducer by the record, as well as completely release the reproducer when the record is raised to normal playing position.

A further object of the present invention is to combine the previously described control or switch means and the stop means so that with a minimum of parts the reproducer may be made to operate both the phonograph control means and the stop or positioning means for the reproducer.

To the accomplishment of the foregoing and such other objects as will hereinafter appear, our invention consists in the phonograph elements and their relation one to the other as herein-after are more particularly described in the specification and sought to be defined in the claims. The specification is accompanied by drawings in which:

Fig. 1 is a partial plan view of a preferred embodiment of our invention;

Fig. 2 is a partial side elevation of the same; Fig. 3 is a detail taken in the plane of the line 3—3 in Fig. 2; and

Fig. 4 is a schematic wiring diagram explanatory of the control circuits of the automatic phonograph.

In automatic phonographs it is desirable to provide control means capable of discriminating between the presence or absence of a record on the phonograph turntable in order to stop the phonograph when the last record has been played. In accordance with the present invention, advantage is taken of the difference in the vertical position of the reproducer, in the presence or absence of a record to control the phonograph, and, more particularly, to operate a switch in the phonograph circuit of an electrically energized phonograph. A number of uses may be thought of for such a switch even in non-automatic phonographs as, for example, to energize a pilot light when the reproducer is turned down to be set upon a record.

In the present case we have illustrated such a switch as applied to an automatic phonograph of the type disclosed in the copending applications aforementioned. A schematic wiring diagram, explanatory of the control circuits of such a phonograph, is shown in Fig. 4 of the drawings, referring to which the automatic phonograph comprises a record turntable 2 which is rotated by a driving motor 4. The record turntable is oscillatable

about a horizontal axis 6 for the record ejecting and record loading operations, and this oscillation is also caused by motor 4, in accordance with the disclosure in the copending applications of Lester L. Jones aforesaid.

The phonograph is preferably of the electrical type, and therefore includes a power unit and amplifier 10 as additional electrically energized equipment. In the present circuit it will be observed that the motor 4 and the power unit 10 are connected electrically in parallel, so that the entire electrical equipment of the phonograph is either energized or deenergized. Between the parallel combination of motor 4 and power unit 10, and the incoming power supply line 12, there is connected, through the leads 14 and 16, the entire control apparatus of the phonograph. Obviously, whenever the circuit between leads 14 and 16 is closed the phonograph is energized, and conversely, whenever the circuit between leads 14 and 16 is opened the phonograph is deenergized.

Between the leads 16 and 14 there is connected a series circuit consisting of lead 18, no-record switch 20, lead 22, power switch 30, and lead 26. No-record switch 20 is operated by vertical movement of the reproducer 60, or vertical oscillation of the reproducer arm 62 about the horizontal pivot 64. Reproducer arm 62 is provided with a finger 66 which is lowered when the reproducer is raised by a record, thereby permitting switch 20 to close. The turntable 2 is considerably smaller in diameter than the record 70 to be played, and consequently in the absence of a record the reproducer 60 remains at a level lower than when resting on a record, in which case the finger 66 opens the switch 20.

Power switch 30 may also be in the form of a jack switch, controlled by a cam 32 rotated by a control knob 34, the switch 30 being opened when control knob 34 is rotated counter-clockwise to the "off" position, and closed when knob 34 is rotated clockwise to the "on" position. Obviously, both the no-record switch 20 and the power switch 30 must be closed in order to energize the phonograph, and this is the case during normal reproducing operation of the phonograph.

In order to prevent the power from being shut off during the record changing operation, in general, by opening of the power switch 30, which places considerable load on the motor when the power is again applied, and also in the case of the particular circuit arrangement so far described, in order to prevent shutting off of the power because of opening of the no-record switch 20 during the record changing operation, a record change completion switch 40 is provided, which may be in the form of a jack switch which is held open by a finger 42 projecting from the oscillatable turntable frame when the turntable is in its normal playing position, but which is closed as soon as the turntable is oscillated for a record loading, record changing, or record rejecting operation. Switch 40 is connected by conductors 44 and 46 in parallel with the series combination of no-record switch 20 and power switch 30, or, in other words, is connected directly across the leads 14 and 16 and therefore serves to energize the phonograph whenever the turntable is tilted and continues to do so until the turntable is restored to its upright position.

A starter switch 50 is connected by leads 52 and 54 directly across the leads 14 and 16, and therefore is also capable of independently energizing the phonograph. This is a non-stick switch, preferably in the form of a jack switch 75

which may be closed by a disk 56 on a reciprocal spindle 58, which preferably is the same spindle that is rotated by knob 34. By pushing knob 34 inward the starter switch 50 is closed 5 and the phonograph is energized. This immediately causes oscillation of turntable 2 about axis 6, which, in turn, closes the record change completion switch 40, so that the starter switch 50 need be closed only for a very short interval of time. 10 Switch 40 remains closed until the record changing operation is completed, but at that time turntable 2 returns to its upright position with a record which raises the reproducer and permits the no-record switch 20 to close. This causes the 15 phonograph to continue to be energized despite the opening of the record change completion switch 40, provided, however, that the power switch 30 is also closed.

The foregoing description of the control circuits in Fig. 4 has been given in order to illustrate 20 one manner of utilizing the present invention, but these circuits are not claimed herein, being described more in detail and claimed in our Patent No. 1,954,247 aforesaid.

25 Referring now to Figs. 1, 2, and 3 of the drawings, the record 70 is carried by a turntable 2, while the reproducer 60 is carried on a vertically oscillatable reproducer arm 62, articulated by means of a horizontal pivot 64, to a horizontally oscillatable reproducer arm 68, carried by a post 72. In the specific structural arrangement here disclosed the reproducer arm 68 consists of a pair of tubular supports between which there is nested a contact switch 20 comprising a movable spring 30 blade 74 and a fixed blade 76. The vertically oscillatable reproducer arm 62 has fixed thereto an extension or finger 66, the upper surface of 35 which is arranged to bear against a block of insulation 78 fixed to the movable switch blade 74. As is clearly illustrated in Fig. 2, when the reproducer 60 drops below the normal playing level 40 the finger 66 presses the switch blade 74 upwardly out of contact with the lower contact 76, thereby opening the switch. When the reproducer 60 is raised by engagement with a record 45 to the broken line position 60' the finger is lowered to the position 66', and the switch 20 is permitted to close.

50 It will be obvious that if the reproducer 60 is positioned at a point near the periphery of a record to be played during the upward oscillation of the record, the resulting movement of the reproducer may be used to discriminate between the presence and absence of a record on the turntable 2, for in the absence of a record the reproducer will not be elevated, the turntable being considerably smaller in diameter than the record, and therefore clearing the reproducer. The 55 downward movement of the reproducer in the absence of a record may be limited by any conventional stop means or, as in the case here illustrated, by the contact of the finger 66 with the movable switch blade 74. It will be clear that if desired the turntable 2 may be made as large in 60 diameter as the records to be played, and the movement of the reproducer equivalent to the thickness of a record may be taken advantage of to operate the switch, but the present arrangement is preferred because it provides greater 65 movement, and therefore more certain operation.

70 It has been assumed that the reproducer is positioned at a point adjacent the periphery of the record during the record changing operation. 75 To accomplish this any one of a number of known

means, such as the spring 140, may be used to lightly urge reproducer 60 inwardly toward a fixed stop 80, mounted upon a post 82 which, in turn, is rigidly attached to the stationary chassis of the phonograph. The finger 66 is provided with means for cooperating with the stop 80, here exemplified by a stepped lug 84, depending from the finger 66. As is evident from an inspection of Figs. 2 and 3, when the reproducer is depressed the lug 84 is elevated to engage the end of the 10 stop 80. When the reproducer is raised by a record the lug 84 is lowered to the position 84', thereby releasing or freeing the reproducer for inward movement over the surface of the record.

15 The stop 80 may be movable to accommodate different sizes of record, but in the present case it is assumed that only one size of record is to be played, say ten inch records, and the stop 80 is fixed. The position of the tip or end of the stop 80 is selected to stop the reproducer, which is assumed to be very lightly urged inward by a spring, at a point over the blank peripheral margin of the record, so that this position is not critical and may be made to accommodate different records regardless of the exact diameter 20 at which the first sound groove begins. The reproducer stylus is moved into the first sound groove, preferably by the drag of the record on the reproducer stylus. To accomplish this the total length of the reproducer arm is made substantially greater than the distance between the center of oscillation of the reproducer arm 72 and the conventional approximately radial (relative to the record) arc of reproducer travel over the record indicated at 86. The strenuous effort heretofore made to obtain the conventional path is illustrated, for example, in the U. S. patent to Jonasson, No. 1,232,807, granted July 10, 1917. More generally, the record and reproducer stylus 25 are brought into contact at a point the motion of which or the tangent to which is at a substantial angle inwardly of the record relative to the longitudinal axis of the reproducer arm, so that the movement of the record tends to drag the stylus toward the first sound groove. 30

35 With such an arrangement any effective lengthening of the reproducer arm tends to cause the reproducer arm to oscillate inwardly of the record. For example, in Fig. 2 the movement of the reproducer arm from the position 60 to the position 60' during the upward oscillation of the turntable 2 causes an effective lengthening of the reproducer arm. Assuming the stylus to be resting in a sound groove, the stylus will then be 40 moved from the position 90 to the position 92 in Fig. 1 of the drawings. This causes an oscillation of the reproducer arm from the position 94 to the position 96. 45

50 A similar movement inwardly of the reproducer is caused by the horizontal component of motion of the upwardly oscillated record. The difference in horizontal location of the centering pin of the turntable in the positions 2 and 2' in Fig. 2 may be taken as an example. This causes a corresponding movement of the reproducer stylus along the groove of the record, the change being illustrated by the movement from the point 93 to the point 90 in Fig. 1. This causes an oscillation of the reproducer arm from the position 100 to the 55 position 94. These movements, of course, do not take place separately but concurrently, and the broken line positions have been drawn more to help explain the conditions which arise than to accurately portray a specific instance to scale. 60

When the record and reproducer come into contact the stylus is on the blank margin of the record rather than in a sound groove, but slight consideration will show that allowance must be made for this movement, for otherwise the reproducer will be forced outwardly on the margin of the record. To overcome this difficulty the tip of the stop 80 is sloped as is best illustrated at 102 in Fig. 3. This slope may, if desired, be determined by the displacement between the center lines 100 and 96 in Fig. 1. A moment's reflection will show that by reason of the slope 102 the stop means 80 and the lug or engaging means 84 are so related that the reproducer 60 is permitted to move inwardly of the record as the record raises the reproducer, in addition to being completely freed for inward movement when the record has been raised to its normal playing position.

From the foregoing description the many uses and advantages of our invention will, for the most part, be apparent. We provide phonograph control means and, more specifically, a no-record switch for an automatic phonograph which is operated in a very simple and certain manner by movement of the reproducer without necessitating the use of additional special equipment other than the switch itself. Stop means is provided for positioning the reproducer at a point adjacent the periphery of a record to be played, and the reproducer is released for inward movement when the record and reproducer are brought into engagement. The stop means is so arranged that the reproducer is permitted to move inwardly of the record as the record is being raised in contact with the reproducer. A single element added to the reproducer arm functions to operate the no-record switch and to engage a simple fixed stop to properly position the reproducer and to limit the downward movement of the reproducer when the reproducer is not supported by a record.

It will be apparent that while we have shown and described our invention in the preferred form, many changes and modifications may be made in the structure disclosed without departing from the spirit of the invention, defined in the following claims.

We claim:

1. In an automatic phonograph in which the reproducer is reciprocable across the record and toward and from the record, and the turntable and a record to be played are moved upwardly into playing contact with the reproducer positioned near the periphery of the record, means to move the reproducer inwardly, a fixed stop for arresting the motion of the reproducer near the periphery of the record, and means moved with the reproducer for engaging the stop when the reproducer drops to a level lower than when resting on a record, said means being disengaged from the stop when the reproducer is raised by a record to be played.

2. An automatic phonograph comprising a reproducer arranged for reciprocation across and toward and from a record, a turntable substantially smaller in diameter than the records to be played, means to raise the turntable and a record carried thereby into playing contact with the reproducer, means for moving the reproducer inwardly, a fixed stop for arresting the movement of the reproducer near the periphery of the record, and means moved with the reproducer for engaging the stop when the reproducer drops to a level lower than when resting on a record, said means being disengaged from the stop when the reproducer is raised by a record to be played.

3. An automatic phonograph comprising a reproducer, a horizontally reciprocable reproducer arm for carrying said reproducer, said arm being articulated at an intermediate point in order to permit of oscillation of the reproducer toward and from the record, a turntable, means to raise the turntable and a record carried thereby into playing contact with the reproducer, and means for locating the reproducer near the periphery of the record comprising a stop on the phonograph chassis and means on the articulated portion of the reproducer arm extending rearwardly therefrom for engaging the stop when the reproducer arm moves to a level lower than when resting on a record, said means being moved below and disengaged from the stop when the reproducer arm is moved upwardly by a record to be played.

4. An automatic phonograph comprising a reproducer, a horizontally and vertically oscillatable reproducer arm arranged for reciprocation across and toward and from a record, a record turntable arranged to be raised in order to bring a record carried thereby into contact with said reproducer, stop means, and means on said reproducer arm for engaging said stop means to position the reproducer at a point adjacent the periphery of a record to be played, said stop means and engaging means having relatively biased surfaces so related that the reproducer is permitted to move limitedly inwardly of the record during the brief time that the reproducer is being raised by the record, and is thereafter completely freed for inward movement when the record is raised to normal playing position.

5. An automatic phonograph comprising a reproducer, a horizontally oscillatable reproducer arm substantially longer than the distance between its center of oscillation and the conventional approximately radial (relative to the record) arc of reproducer travel over the record, a record turntable oscillatable about a horizontal axis in order to bring a record carried thereby into contact with said reproducer, stop means, means on said reproducer for engaging said stop means to position the reproducer at a point adjacent the periphery of a record to be played, said stop means and engaging means being so related that the reproducer is permitted to move limitedly inwardly of the record during the brief period that the reproducer is being raised by the record, and is then completely freed for inward movement when the record is raised to normal playing position.

6. An automatic phonograph comprising a reproducer, a horizontally and vertically oscillatable reproducer arm substantially longer than the distance between its center of oscillation and the conventional approximately radial (relative to the record) arc of reproducer travel over the record, a record turntable oscillatable about a horizontal axis in order to bring a record carried thereby into contact with said reproducer, stop means, means urging said reproducer arm toward said stop means, and means on said reproducer arm for engaging said stop means to position the reproducer at a point adjacent the periphery of a record to be played, said stop means and engaging means being so related that the reproducer is permitted to move limitedly inwardly of the record during the brief period that the reproducer is being raised by the record, and is then completely freed for inward movement when the record is raised to normal playing position.

7. An automatic phonograph comprising a re-

- producer, a horizontally oscillatable reproducer arm substantially longer than the distance between its center of oscillation and the conventional approximately radial (relative to the record) 5 arc of reproducer travel over the record, said arm being articulated at an intermediate point by a horizontal pivot in order to permit of vertical reciprocation of the reproducer, a record turntable oscillatable about a horizontal axis in order to 10 bring a record carried thereby into contact with said reproducer, fixed stop means, and means on said reproducer arm for engaging said stop means to position the reproducer at a point adjacent the periphery of a record to be played, said stop 15 means and engaging means being so related that the reproducer is permitted to move limitedly inwardly of the record during the brief period that the reproducer is being raised by the record, and is then completely freed for inward 20 movement when the record is raised to normal playing position.
8. An automatic phonograph comprising a reproducer, a horizontally and vertically reciprocable reproducer arm for carrying said reproducer, 25 a record turntable, means to bring a record carried thereby and the reproducer into engagement, means to move the reproducer inwardly, a fixed stop for arresting inward movement and thereby positioning said reproducer at a point adjacent 30 the periphery of the record, a no-record switch, and means responsive to vertical reciprocation of the reproducer for releasing the reproducer from the stop for inward movement when the reproducer rests on a record to be played, and for 35 operating the no-record switch in response to the presence of a record on the turntable.
9. An automatic phonograph comprising a reproducer, a horizontally and vertically reciprocable reproducer arm for carrying said reproducer, engaging means on said arm, a record turntable 40 movable upwardly for bringing a record carried thereby into contact with the reproducer, a stop for engaging said engaging means and thereby positioning said reproducer at a point adjacent 45 the periphery of the record, a no-record switch, and means responsive to vertical reciprocation of the reproducer for releasing the reproducer for inward movement when the reproducer is raised by a record to be played, and for operating the 50 no-record switch in response to the presence of a record on the turntable, said stop means and engaging means being so related that the reproducer is freed for limited movement inwardly during the brief period that the reproducer is 55 being raised by the record.
10. An automatic phonograph comprising a reproducer, a horizontally and vertically reciprocable reproducer arm for carrying said reproducer, means tending to move the reproducer inwardly, a record turntable substantially smaller 60 in diameter than the records to be played and movable upwardly for bringing a record carried thereby into contact with the reproducer, a fixed stop for arresting inward movement and thereby positioning said reproducer at a point adjacent the periphery of the record, a no-record switch, and means responsive to vertical reciprocation of the reproducer for releasing the reproducer from the stop for inward movement when the reproducer is raised by a record to be played, and for 10 operating the no-record switch in response to the presence of a record on the turntable.
11. An automatic phonograph comprising a reproducer, a horizontally reciprocable reproducer arm for carrying said reproducer, said arm being articulated at an intermediate point by a horizontal pivot in order to permit of movement of the reproducer toward and from the record, a record turntable substantially smaller in diameter than the records to be played and movable upwardly for bringing a record carried thereby into contact with the reproducer, a stop for positioning said reproducer at a point adjacent the periphery of the record, means on the articulated portion of the reproducer arm extending rearwardly therefrom for engaging the stop, a no-record switch carried by said reproducer arm and operatively connected to the said engaging means, whereby upward movement of the reproducer about the horizontal pivot moves the engaging means below the stop and thereby releases the reproducer for inward movement when the reproducer is raised by a record to be played, and operates the no-record switch in response to the presence of a record on the turntable.
12. An automatic phonograph comprising a reproducer, a horizontally reciprocable reproducer arm for carrying said reproducer, said arm being articulated at an intermediate point by a horizontal pivot in order to permit of movement 40 of the reproducer toward and from the record, a record turntable substantially smaller in diameter than the records to be played and movable upwardly for bringing a record carried thereby into contact with the reproducer, a fixed stop 45 for positioning said reproducer at a point adjacent the periphery of the record, a no-record switch carried by said reproducer arm, and a control finger secured to the articulated part of said arm and thereby responsive to movement 50 of the reproducer about the horizontal pivot for limiting the downward movement of the reproducer when the reproducer is not supported by a record, for releasing the reproducer for inward movement when the reproducer is raised by a record to be played, and for closing the no-record switch in response to the presence of a record on the turntable.

LESTER L. JONES.
THOMAS E. PIAZZE. 60
